[57] CLAIM

The ornamental design for a battery pack for a portable communications device, as shown and described.

DESCRIPTION

FIG. 1 is a top plan view of a battery pack for a portable communication device showing our new design;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top, right rear isometric view thereof; and,

FIG. 8 is a top, left front isometric view thereof.

The broken line showing throughout the drawing figures is included for the purpose of illustrating environmental structure only and forms no part of the claimed design.
